UNITED STATES PATENT OFFICE.

NATHAN WISE, OF NEW YORK, N. Y.

MULTIPLE INCANDESCENT ELECTRIC LAMP.

Application filed February 7, 1919. Serial No. 275,586.

To all whom it may concern:

Be it known that I, NATHAN WISE, a citizen of the United States, residing at New York city, in the county of New York and State of New York, have invented certain new and useful Improvements in Multiple Incandescent Electric Lamps, of which the following is a specification.

The invention provides an electric lamp, 10 of the incandescent type embodying a plurality of metal filaments, wherein the filaments are disposed one above the other and are adapted to be brought successively into circuit from the bottom filament upward, 15 thereby preventing short circuiting or impairment of the lower filaments by particles of an upper filament falling thereon when burned out, broken or otherwise disqualified for further service.

20 The invention provides novel circuit closing means to admit of any filament being brought into circuit and the latter made secure against any possible opening incident to jar or vibration, the circuit closing means including a screw cap and a complementary cooperating screw member, whereby the closing is made positive and binding by a screw-thread action.

25 The drawing illustrates a preferred embodiment of the invention. However, it is to be understood that in adapting the same to meet different conditions, various changes in the form, proportion, and minor details of construction may be resorted to without departing from the nature of the invention 35 as claimed hereinafter.

The drawing hereto attached illustrates adaptations of the invention of which,

Fig. 1 is a vertical central section of a 40 lamp of the preferred type.

Fig. 2 is an end view of the lamp head or base.

Fig. 3 is a diagram showing more clearly the circuit and a cross section of a portion of the lamp head or base.

Corresponding and like parts are referred to in the following description and indicated in the several views of the drawing by like reference characters.

The lamp bulb or globe 1 may be of any usual construction and is formed with a neck 2 which is closed by means of a head or plug. Within the neck 2 is disposed the usual supporting stem 3 of glass or like material, the end of the neck being closed by a suitable filling 4 of cement or composi-

tion. A section 5 is placed upon the filling 4 and may be of any insulating material such as vulcanite, papier mâché or other suitable material. A metal sleeve 6 is fitted 60 to the lamp head and encompasses the parts 4 and 5 and constitutes one of the lamp terminals in a manner well understood.

Filaments 7 and 8 are located within the lamp globe or bulb 1 and are disposed one 65 above the other, each of the filaments consisting of a wire coil bent into approximately circular form as shown most clearly in Fig. 3. Insulating elements 9 are centrally disposed within the lamp bulb and 70 are connected by means of a stem 10. Braces 11 connect each of the elements 9 with the respective filaments to hold the latter in given position. A supporting wire 12 is attached to the stem 10 and is electrically 75 connected with the lower filament 8. A wire 13 is electrically connected with each of the filaments 7 and 8 and constitutes a return common thereto. A wire 14 is electrically connected with the upper filament 80 7. The several wires 12, 13 and 14 constitute the leads between the lamp terminals and the filaments and are connected with and supported by the stem 3 in any usual 85 or preferred way. The wire 13 is electrically connected with the metal sleeve 6. The wire 14 is electrically connected with the terminal or contact 16 which is centrally disposed upon the lamp base or head. The wire 12 is electrically connected with a terminal or contact 17 which is mounted upon the base or head and is of annular form comprising a base and collar, the latter being externally screw-threaded. The upper or 90 outer face of the section 5 is formed with an annular recess in which is fitted the base portion of the annular terminal 17 and with a central projection 18 which passes through the exteriorly threaded collar of the annular terminal 17 and receives at its outer end the 95 terminal 16. The central projection 18 extends beyond the collar of the annular lamp terminal 17 and beyond the recess portion of the section 5, thereby preventing casual short circuiting of the terminals 16 and 17. 100

A cap 19 is internally screw-threaded to snugly fit the threaded collar of the annular terminal 17 and when in position completely encloses the lamp terminal 16. Thus when the lamp is in service the lower filament 8 only is in circuit, the filament 7 being held in reserve to be brought into

service when the filament 8 becomes disqualified for further use from any cause. In this manner the lowermost filament is first utilized and when unfitted for further use 5 the filament 7 is brought into active position by removing the cap 19 so as to expose the terminal 16. It is to be understood that the lamp is of usual construction to be plugged into the ordinary socket which closes the circuit 10 through the sleeve 6 and the central terminal such as 16 or 19 whichever one is exposed to make contact with the central contact of the lamp socket. Insulation 20 is disposed within the cap 19 to guard against 15 short circuiting of the terminals 16 and 17 by the cap.

The annular terminal 17 has its base portion provided with a plurality of projections 21 which pass through vertical openings 22 20 formed in the section 5, the terminal portions of the projections 21 being bent inwardly to retain the terminal 17 in position and prevent turning thereof when rotating the cap 19 to screw it upon or unscrew it from the collar of the terminal 17. Radial openings 23 are formed in the section 5 and intersect with the vertical openings 22. A suitable instrument or tool is 25 adapted to be inserted in the openings 23 to bend or clinch the terminals of the projections 21. The screw cap 19 makes a positive and binding connection with the exteriorly threaded collar of the annular contact 17 and by reason of its function 30 constitutes a displaceable terminal which may be thrown aside or discarded after the lower filament 8 has been burned out or otherwise unfitted for further service.

When the screw cap 19 is in position the 35 lamp is adapted for service in substantially the same manner as the ordinary incandescent lamp and when plugged into a socket and the current turned on, the circuit is through the lower filament 8. When the 40 filament 8 becomes ineffective for further service the filament 7 is brought into active position by removing the screw cap 19 which is discarded. The circuit through the lamp 45 is now by way of the terminals 16 and 6. By having the lowermost filament in service 50 at the outset any particles falling therefrom when the filament becomes burned out or broken will not light upon and tend to short circuit or otherwise impair the efficiency 55 of any other filament such as would be the case if an upper filament was first brought into service. The screw cap 19 provides simple means for insuring a firm and positive connection and also acts as a protector 60 for the terminal 16 of the reserved filament.

Having thus fully described my invention, what I claim as new and desire to secure by Letters Patent is:—

1. In an incandescent electric lamp, in-

cluding a plurality of filaments and lamp terminals, an annular member in electric connection with one of the lamp terminals, and a tubular member adapted to be attached and detached to said annular member 70 and encircling and extending above one of the other lamp terminals.

2. In an incandescent electric lamp, including a plurality of filaments and lamp terminals, an annular member in electric 75 connection with one of the lamp terminals and comprising a base and a collar, and a cap constituting a lamp terminal and covering one of the other lamp terminals and detachably mounted upon the collar. 80

3. In an incandescent electric lamp, including a plurality of filaments, and lamp terminals, and having its base or head provided with a centrally disposed projection, an annular member in electric connection 85 with one of the lamp terminals and disposed on the base and having a collar fitted upon the said projection, and a cap constituting a lamp terminal and covering one of the other lamp terminals and detachably mounted 90 upon the threaded collar.

4. In an incandescent electric lamp, including a plurality of filaments and lamp terminals, and having the outer end of its base or head recessed and provided with a 95 central projection, an annular member in electric connection with one of the lamp terminals and comprising a base portion and a collar, the latter snugly fitting the projection of the lamp head, and a cap constituting 100 a lamp terminal and covering one of the other lamp terminals and detachably mounted upon said collar.

5. In an incandescent electric lamp, including a plurality of filaments and lamp 105 terminals, one of such terminals consisting of an annular contact member encircling another one of the terminals and a cap adapted to be fitted to the annular contact member and enclose the terminal encircled 110 thereby.

6. In an incandescent electric lamp, including a plurality of filaments and lamp terminals, one of such terminals consisting of an annular contact member encircling 115 another one of the terminals and a cap adapted to be fitted to the annular contact member and enclose the terminal encircled thereby, said cap being displaceable to expose the enclosed terminal to admit of the 120 filament electrically connected therewith being brought into active service.

7. In an incandescent electric lamp, including a plurality of filaments, and lamp terminals and having the lamp base formed at its outer end with an annular recess and a central projection, one of said terminals being supported upon the outer end of said projection, an annular member disposed in the recess of the lamp base and constituting 125 130

- a lamp terminal and having an externally screw-threaded collar snugly fitting the said projection, and an internally screw-threaded cap engaging the said collar and the base 5 thereof and enclosing the lamp terminal mounted upon the projection of the lamp head.
8. In an incandescent electric lamp, including a plurality of filaments and lamp terminals, an element in electric connection with one of the lamp terminals and constituting one of the active contacts and adapted to be detached from the lamp without injury thereto, so as to expose another 10 of the lamp terminals in position to make positive electric contact.
9. In an incandescent electric lamp, including a plurality of filaments and lamp terminals, a tubular attachable and detachable element having electric connection with one of the lamp terminals and constituting the active contact and a cutout for one of the other lamp terminals and when detached admitting of such terminal being brought 15 into operative position.
10. In an incandescent electric lamp, including two filaments and corresponding lamp terminals, a tubular element in electric connection with one of the lamp terminals 20 and adapted to be attached to and detached therefrom and constituting the active contact and cutting the other terminal out of action and so arranged that when detached the other lamp terminal is brought into active 25 contacting position.
11. In an incandescent electric lamp, upper and lower metal filaments of approximately circular form, upper and lower insulator supporting elements, braces connecting the insulator elements with the respective filaments, a stem connecting the insulator elements, a lead wire forming a support for the said stem and insulator element and electrically connected with one of the 30 filaments, lamp terminals electrically connected with the filaments, one of said ter- 35
- minals being of annular form and having an externally screw-threaded collar which encircles one of the lamp terminals and an internally screw-threaded cap mounted upon 50 the said threaded collar and enclosing the lamp terminal encircled by said collar.
12. An incandescent electric lamp, comprising a plurality of filaments, one common terminal for all of the filaments, and a separate terminal for each of the filaments, a cap in electrical connection with one of the lamp terminals and forming a cover for and insulated from one of the other lamp terminals. 55
13. An incandescent electric lamp having two filaments arranged one above the other, a common terminal for both filaments, a separate terminal for each of the filaments, a cap attachably and detachably fitting over 60 and insulated from one of the terminals and forming electrical connection with the separate terminal of the lower filament, the cap being adapted to be readily detached when the lower filament is rendered useless 65 so as to expose the terminal of the upper filament. 70
14. In an incandescent electric lamp, including a plurality of filaments and lamp terminals, an annular member exteriorly 75 screw-threaded and in electric connection with one of the lamp terminals, and an interiorly screw-threaded cap detachably fitted to said annular member and covering one of the other lamp terminals. 80
15. In an incandescent electric lamp, including a plurality of filaments and lamp terminals, an annular member in electric connection with one of the lamp terminals 85 and comprising a base and an exteriorly screw-threaded collar, and an interiorly screw-threaded cap constituting a lamp terminal and covering one of the other lamp terminals and detachably mounted upon the screw-threaded collar. 90

In testimony whereof I affix my signature.
NATHAN WISE.
